CLOCK

Charles A. McLeod, Oak Park, Ill., assignor to Sunbeam Corporation, Chicago, Ill., a corporation of Illinois

Continuation of design applications Ser. Nos. 73,574 and 73,575, Feb. 14, 1963. This application Mar. 30, 1964, Ser. No. 79,372

Term of patent 14 years

(Cl. D42—7)

Fig. 1.

Fig. 2.

FIG. 6

FIG. 7

FIG. 9.

FIG. 10.

FIG. 1 is a front elevational view of a clock showing the new design;

FIG. 2 is a top plan view thereof;

FIG. 3 is an enlarged sectional view taken along the section line 3-3 of FIG. 1;

FIG. 4 is an enlarged sectional view taken along the section line 4-4 of FIG. 1;

FIG. 5 is an enlarged sectional view taken along the section line 5-5 of FIG. 1;

FIG. 6 is a front elevational view of a clock showing a modification of my new design;

FIG. 7 is a top plan view thereof;

FIG. 8 is an enlarged sectional view taken along the section line 8-8 of FIG. 6;

FIG. 9 is an enlarged sectional view taken along the section line 9-9 of FIG. 6; and

FIG. 10 is an enlarged sectional view taken along the section line 10-10 of FIG. 6.

In the design of FIGS. 1-5 the clock is provided with a dozen radial spikes aligned with the dozen hour marks of the dial face. The radial spikes at the three, six, nine

and twelve hour marks are longer than the others, and they are recessed at their inner ends, as shown. In the modification of FIGS. 6-10 the radial spikes at the three, six, nine and twelve hour marks each comprise two spaced spikes, one within the other, as shown.

This application is a continuation of my applications D. 73,574 and D. 73,575, both filed February 14, 1963, and now abandoned.

I claim:

The ornamental design for a clock, as shown and described.
